MOTOR EFFICIENCY INDICATOR

Filed May 23, 1929

INVENTOR

Houston Taylor

UNITED STATES PATENT OFFICE

HUSTON TAYLOR, OF PITTSBURGH, PENNSYLVANIA

MOTOR-EFFICIENCY INDICATOR

Application filed May 23, 1929. Serial No. 365,502.

This invention relates to an indicator which checks the performance of a motor driven vehicle with an ideal standard for that particular vehicle.

5 It relates to a motor power meter which indicates on a dial with adjustable numbers the performance of the vehicle relative to a previous setting of the dial.

It relates further to a registering device 10 which is adjusted to the ideal performance of a motor driven vehicle to which standard future performances may be compared, by the operation of said device.

It relates to a motor vehicle performance 15 indicator, having a dial with adjustable graduated numbers indicating various speeds in miles per hour, adjusted to an ideal performance of said motor vehicle to which future performances may be compared by an 20 indicating hand on said indicator, and operable by means of the throttle connection which controls the fuel supply.

25 My invention relates to an indicating device and a method of determining whether a motor driven vehicle to which it is applied is performing at its best efficiency.

30 Various other novel features and constructions will appear as an understanding of the invention is had from the following description taken in connection with the accompanying drawings, in which

35 Figure 1 is a side elevation of the installation of a motor power indicator in accordance with my invention, on a fragmental section of an automobile.

Figure 2 is a front elevation of the dial with graduated adjustable numbers and index hand of my invention.

40 Figure 3 is a side sectional elevation of the motor power indicator.

Figure 4 is a different construction of the indicator in which the dial turns on its vertical axis and the indicating hand remains stationary.

45 Like reference characters refer to like parts in the different figures of the drawings. The indicator frame 1 is installed at some easily visible location as on the instrument board 7 of an automobile, said frame 1 forms a dial here shown in the shape of an semi-circle,

having a graduated series of number plates 3 indicating various speeds at miles per hour that may be moved along the dial and adjusted to the ideal performance of said vehicle relative to the position of hand 2 55 which is operated around the face of the dial by cable 4 secured to the throttle control 5 of the fuel for said vehicle, and compared with the speed as shown on the speedometer (not shown on drawings).

60 Frame 1 has two flanges 13 and 13^a extending downward with apertures 14 and 14^a in alignment. Through said apertures 14 and 14^a a horizontal extension of hand 2 extends through and is rotatable in said apertures. Said hand 2 is operated by means of a spiral twist in its horizontal section 8 65 responding to a slot in the flange 15 of operating slide 9 which is drawn through and guided by slot 16 in flange 13^a of frame 1 by 70 means of cable 4 when accelerator 12 moves throttle 20 on carburetor 19 by rod 5 to which cable 4 is attached, and reciprocated back and forward by spring 11 and cable 4 according to the power desired.

75 Figure 4 illustrates an indicator made of a flat cylinder rotatable about vertical axis 8^a. The adjustable numbers are located around the surface of the cylinder, which is operable relative to index point 2^a by means of cable 80 connection with the throttle control, and return spring 11^a.

I do not limit my invention to the operating mechanism shown in figures on the drawing, as the spiral bar 8 and slot 17 movement or the lever movement of Figure 4. The desired movement may be obtained by gears, levers, ratchets, pulleys, etc. or by the hand accelerator indicating on an adjustable dial the position of the throttle (not shown).

85 To operate my invention, it is properly installed on a motor driven vehicle, the dial mechanism is secured by clamp or bolts to the sill of the instrument board, and the cable 4 is secured to the throttle control so that the movement of hand 2 corresponds to the movement of the throttle, and is sensitive thereto. Then the condition of the automobile must 95 be at its best,—free of carbon, valves right, carburetor properly adjusted, spark plugs and 100

terminals correct, brakes free, lubrication and timing accurate,—a good grade of gasoline chosen, the car warmed up to its ideal running condition. The car is then driven along 5 a level road at certain chosen speeds and the corresponding numbers 3 on dial 1 moved to register with the hand 2 at their respective speeds, as shown on a speedometer. To illustrate, drive twenty miles an hour, according 10 to speedometer, without slowing or accelerating, move number 20 so that its center line will register with point of hand 2. Do the same with other numbers at their respective speeds. This setting of the dial will be considered 15 the ideal performance of the particular car on which it is installed, and the standard to which later performance is checked by means of this invention of the motor power indicator. This indicator will show on the 20 dial any lack of power for a particular car at the various chosen speeds. If carbon has lowered its motor efficiency, if spark plugs, wiring, or valves are bad, if poor gasoline has been put in, if brakes are dragging, or anything 25 has crept in to lower the efficiency of the car, it can be at once noticed by comparing the speedometer reading with the reading of the indicator, under similar conditions at which the indicator was set.

30 What I claim and desire to secure by Letters Patent is:

1. A registering device installed on the instrument board of an automobile, comprising a frame forming a dial on which graduated 35 numbers are manually adjustable, and flanges supporting a rotatable element which operates the index hand on said dial by having a spiral section which responds to a longitudinal movement of an enclosing slot operated by a cable to the throttle control on the carburetor and returned by means of a coil spring around said spiral section of the hand operating element.

40 2. An indicator of the performance of a motor driven vehicle with various fuels, under differing engine conditions, etc., comprising a fixed element and a movable element disposed adjacent one another so that their 45 relative position is apparent to the operator of the vehicle, a shiftable index on one of said elements, and mechanism connected to and actuated by the fuel throttle of said vehicle to cause relative motion indicated by said index between said elements in proportion to the extent of movement of said throttle.

50 3. An indicator of the performance of a motor driven vehicle with various fuels, under differing engine conditions, etc., comprising a dial, a hand mounted for movement over 55 said dial, an index adjustably connected to said dial so that it may be shifted with respect thereto to show the position of said hand for a selected standard condition of said vehicle, and mechanism operatively connecting 60 said hand to the fuel control mechanism of

65 said engine whereby the position of said hand will vary in accordance with the rate of fuel feed and may readily be compared with said standard shown by said index.

70 4. The method of giving the operator of a motor vehicle a visible indication of the performance of his vehicle, which consists in providing a dial where it may readily be seen by said operator, indicating on said dial the 75 position of an element of the fuel control mechanism at a predetermined speed under conditions selected as standard and making a comparison between the position of said element with respect to said indication on the dial and the indicated speed of the vehicle 80 under differing fuel motor or vehicle conditions.

85 5. The method of giving the operator of a motor vehicle a visible indication of the performance of his vehicle, which consists in providing a dial where it may readily be seen by said operator observing the rate of speed of the vehicle under certain fuel, motor and vehicle conditions, indicating on said dial the position of an element of the fuel 90 control mechanism, at said rate of speed, and making a comparison between the position of said element with respect to said indication on the dial and the speed of the vehicle under differing fuel, motor or vehicle conditions.

95 In testimony whereof, I affix my signature.
HUSTON TAYLOR.
